UNITED STATES PATENT OFFICE.

ALEXANDER D. SCULLY, OF NEW YORK, N. Y.

MECHANICAL ANKLE-MOVEMENT DEVICE FOR ARTIFICIAL LIMBS.

Application filed July 8, 1925. Serial No. 42,197.

To all whom it may concern:

Be it known that I, ALEXANDER D. SCULLY, citizen of the United States, and resident of New York city, in the county of New York and State of New York, have invented certain new and useful Improvements in Mechanical Ankle-Movement Devices for Artificial Limbs, of which the following is a specification.

10 My invention relates to mechanical ankle movement devices for artificial limbs and has a particular reference to articulated devices adapted to connect the foot and calf portions of an artificial limb.

15 The object of my invention is to provide a mechanically strong device for the above purpose, with a limited degree of freedom of movement in two directions, provided with efficient means of lubrication

20 of the frictional surfaces.

I further provide my device with improved means of taking up any lost motion and looseness which may develop in pivoting joints on account of the wear of the

25 frictional surfaces.

My invention is more fully described in

the accompanying specification and drawing

in which—

Fig. 1 is an elevation of my device with the artificial foot shown with dotted lines, and Fig. 2 is a sectional elevation taken from another angle.

My device consists of a lower clevis 1 with a threaded extension 2 provided with 35 a nut 3 and a washer 4. The clevis 1 is clamped to the artificial foot 5 with the nut 3 and is prevented from turning in its position by means of pins 6'. A tapered pin 6 is fitted into the clevis 1 and is prevented 40 from turning by means of a pin 7 which is fitted partly in the side plate of the clevis and partly in the pin 6.

The larger end of the pin 6 is made cylindrical in its portion which is fitted in the clevis in order to facilitate its adjustment lengthwise. The pin is made shorter than the distance between the outer cheeks of the clevis, and the remaining space at the small end of the pin is filled with filling washers 8.

The pin is provided with threaded holes 9 at both ends for screws 10. These screws are provided with flat heads 11 of a larger diameter than the pin 6 and have recesses 12 on the inside for the ends of the pin. A connecting block 13 is fitted between the

sides of the clevis 1 and is provided with a central tapered hole for the pin 6. The rotative movement of the block 13 is limited by means of the flat edges 14 and 15, bearing 60 against the inner surface 16 of the clevis. The edge 14 is placed at a short distance from the surface 16, thereby allowing but a slight motion in this direction, corresponding to the straightening movement of the 65 foot in relation to the calf 17. The front edge 15 is raised at a higher angle, thereby allowing a greater angle of flexure corresponding to the angle of flexure during normal process of walking.

Rubber or similar resilient blocks 18' are wedged between the foot 5 and the calf 17, so as to prevent any lost motion or chattering between these two members of the artificial foot.

The upper portion of the block 13 is fitted in an upper clevis 18 and is pivoted on a tapered pin 19 built similarly to the pin 6. It is made shorter than the distance between the outer surfaces of the sides of the clevis 18, and the remaining space at the small end of the pin is filled with filling adjusting washers 20. The ends of the pin 19 are provided with threaded holes for clamping and adjusting screws 21 with large flat heads 22. These heads have inside recesses 23 for the ends of the pin 19. A key pin 24 is fitted partly in the pin at the large end and partly in the side of the clevis 18 in order to prevent the pin 19 from turning. 90 The holes 24' in the screw heads are provided for turning the screws (by means of a spanner wrench), similarly to holes 25 in the screws 10.

The clevis 18 is fitted into the calf portion of the artificial foot and is clamped by means of a threaded extension 25' with a nut 26 and a washer 27. Pins 28 prevent the clevis from turning in its place.

In order to provide a system of lubrication for all frictional surfaces the body of the upper clevis 18 is drilled through the central portion (hole 29) with a side vent 30 registering with an oil hole 31 in the calf 17.

The pins 6 and 18 have circular recesses or grooves 32 in their middle portions corresponding to the hole 29 in the body of the clevis 18 and the holes 33 and 34 in the connecting block 13. With this arrangement 110 the oil, when poured into the oil hole 31, will flow to the pins 6 and 19 and will spread

over all of the frictional surfaces. Longitudinal slots 35 in the block 13 will help to spread the oil along the pins.

The upper portion of the block 13 is provided with shoulders 36 placed at a small angle with the inside surface 37 of the upper clevis, so as to allow a limited amount of a sidewise tilting movement for the foot 5 in relation to the calf 17, corresponding to

10 the natural side bending of a human angle.

In order to adjust the pins 6 and 18 for wear, the screws 10 and 21 are removed, other screws loosened, one or more adjusting washers 8 or 20 removed, and the screws 15 tightened again, beginning with the screws at the small ends, that is screws 10 and 21. The screws will be accordingly drawn towards small ends, thereby fitting tighter in the connecting block 13.

20 The washer, removed from the small end, may be placed at the larger end in order to have the screws drawn tightly against the pin and washers. This will tend to prevent their loosening in service.

25 Important advantages of my device are that it allows natural degree of freedom in two directions for the artificial foot, is easy to lubricate and can be adjusted for wear

so as to eliminate any lost motion or looseness between the respective parts.

Another advantage of my device is that it has two articulated joints at right angles with each other forming an universal joint, which allows the same degree of freedom to move in all directions as there exists in a 35 natural human foot.

I claim as my invention:

In a mechanical ankle movement device, the combination with a lower clevis, a threaded extension on said clevis adapted to 40 be attached to an artificial foot, an upper clevis, a threaded extension on said upper clevis adapted to be attached to an artificial calf, a connecting block slidably fitted into said clevises, tapered pins forming pivoted 45 connections between said clevises and said connecting block, means to prevent said clevises from rotation in said artificial foot and calf, and a plurality of resilient members wedged between said artificial foot and 50 said calf.

Signed at New York, in the county of New York and State of New York, June A. D. 1925.

ALEXANDER D. SCULLY.
